Patented July 5, 1921.

FIG. 1.

FIG. 2.

FIG. 4.

FIG. 3.

William Israel
by
Loyd N. Anderson

ATTORNEY

UNITED STATES PATENT OFFICE.

WILLIAM ISRAEL, OF KINGSTON, PENNSYLVANIA, ASSIGNOR OF ONE-HALF TO
SYDNEY ISRAEL, OF KINGSTON, PENNSYLVANIA.

LAMP-SUPPORTING ATTACHMENT FOR MINERS' CAPS.

1,383,721.

Specification of Letters Patent.

Patented July 5, 1921.

Application filed June 21, 1918. Serial No. 241,305.

To all whom it may concern:

Be it known that I, WILLIAM ISRAEL, a citizen of the United States, residing in Kingston, county of Luzerne, State of Pennsylvania, have invented certain new and useful Improvements in Lamp-Supporting Attachments for Miners' Caps, of which the following is a specification.

There are at present a number of different kinds or styles of miners' lamps being manufactured and which are in use, each kind or style being provided with means peculiar to itself for engagement with the lamp-supporting attachment upon miners' caps, which necessitates each attachment being provided with special means adapting it for use in connection with one particular kind or style of lamp. Heretofore it has been the practice universally to provide lamp-supporting attachments adapted only for one kind or style of lamp. When such lamp-supporting attachment has been or is attached to a cap, only a lamp provided with an attaching means adapted to that particular kind of lamp-supporting attachment could or can be engaged with said supporting attachment.

Such practice of constructing different kinds or types of lamp-supporting attachments, each type or kind being adapted only for use in connection with a lamp provided with a particular kind of attaching means corresponding thereto, is expensive and wasteful of material, time and labor required in the manufacture of the same.

My invention has for its object broadly to obviate this wasteful practice by providing a lamp-supporting attachment having means whereby any known lamp having any of the known means for attaching it to a lamp-supporting attachment may be attached thereto and supported thereon and thereby.

More specifically stated, my invention has for its object to provide a single lamp-supporting attachment for miners' caps provided with a plurality of different means, each adapted for engagement with the attaching means upon the different kinds of lamps now manufactured and in use.

Other objects and advantages of my invention will be specifically referred to and pointed out in the detailed description thereof of which follows or will be apparent from such description.

In order that the practical advantages of my invention may be more fully appreciated, I have illustrated in the drawings constituting and forming a part of this specification an attachment constructed in accordance with my invention, and have also illustrated several different forms of miners' lamps provided with different kinds of attaching means for which the supporting attachment embodying my invention is adapted.

In the said drawings:

Figure 1 is a perspective view of a miner's cap provided with a lamp-supporting attachment constructed in accordance with my invention;

Fig. 2 is a perspective view of a lamp having a specific form of attaching means which is adapted for engagement with means provided therefor in the lamp-supporting attachment shown in Fig. 1;

Fig. 3 is a view taken on the line 3—3 of Fig. 1 showing a portion of the cap in section and showing a portion of the attachment in vertical, longitudinal section, and also showing a lamp with a different kind of attaching means from that shown in Fig. 2 attached to the said lamp-supporting attachment; and

Fig. 4 is a perspective view of another form of lamp having still another form of means for attaching it to the lamp-supporting attachment.

Referring to the drawings, 1 designates a miner's cap constructed as usual of pliable fabric provided with a stiff vizor 2. The lamp-supporting attachment comprises the forwardly and downwardly extending portion 3, secured by means of rivets or equivalent fasteners 4 to the forward edge portion 90 of the vizor 2. The portion 3 extends in substantially parallel relation to the vizor 2. The central portion 5 of the attachment extends upwardly in general parallel relation to the said portion of the cap 1. The upper end of the portion 5 is connected by a bend to a rearwardly extending portion 6 which in turn is connected to a downwardly extending portion 7, the lower end of the latter in turn being connected with a rearwardly extending portion 8, which is connected by rivets or equivalent fasteners 10 to the forward portion of the top of the cap, as is clearly shown in Fig. 1.

In order to adapt the attachment to receive

and support a lamp 11, having a single hook-shaped means 12 as shown in Fig. 3 for engaging the said attachment, I have provided the portion 8 of said attachment with an 5 opening 13, in rear of a central vertical slot 14, provided in the rectangular-shaped portion of the attachment formed by the upper end of the part 5, the portion 6 and the depending portion 7. The said slot opens into 10 a relatively wide opening 15 formed in the upper central portion of the part 5 of the attachment. The presence of the latter opening is to permit relative swinging movement between the lamp 11 and the cap when the 15 wearer of the cap stoops. In other words, when the person wearing a cap stoops down, if he is carrying on the lamp-supporting attachment upon his cap a lamp such as that shown in Fig. 3 of the drawings, the latter 20 will swing out or away from the upright portion 5 of the said attachment and the end of the hook 12 will swing forward and project into the opening 15.

If, instead of using a lamp such as that 25 shown in Fig. 3 of the drawings, a lamp such as is shown in Fig. 2 be used, it can be secured in position upon the supporting attachment by inserting the two prongs 16, which are spaced from each other, through 30 the spaced openings 17 provided in the horizontal portion 6 of the lamp supporting attachment. It may be that instead of lamps having attachments such as those shown at 16 and 12 in Figs. 2 and 3 of the drawings, a 35 lamp having a single flat plate-like attaching means 18, as shown in Fig. 4 of the drawings, may be employed. In that case it will be necessary to provide a corresponding opening in the lamp-supporting attachment for the 40 reception of such flat attaching means 18. Such an opening is shown at 20 in Fig. 1 of the drawings. This opening extends at right angles to the slot 14 previously referred to and is formed by cutting notches in the horizontal bridge portion 6 of the attachment 45 upon opposite sides of the said slot 14, as is clearly shown in Fig. 1 of the drawings.

It may be that instead of having a plurality of attaching means such as 16 shown 50 in Fig. 2, the lamp may have a single, relatively wide attaching means. In such case, a corresponding attaching means should be provided upon the lamp-supporting attachment. Such means is shown at 21 in Fig. 1 55 of the drawings.

Although not illustrated, such lamps are constructed; that is,—lamps having a single relatively wide attaching means.

It will be seen that I have provided a single 60 lamp-supporting attachment for miners' caps which is capable of supporting four different kinds or types of lamps; that is, lamps having four different kinds of means by which the same may be attached or secured to and

supported upon the lamp-supporting attachment, thereby rendering unnecessary the manufacture of four different kinds of lamp-supporting attachments for supporting the four different kinds or types of lamps. In this way a great saving of material is effected 65 as well as great economy in the cost of material and manufacture. 70

It will be understood that the different openings as shown and described may be formed while the strip of which the attachment is constructed is in a flat or unformed state and that after the said openings shall have been cut through the said strip, the latter may be formed into the shape as shown 75 in Fig. 1.

In connection with the staple-like holding means 21 which in fact forms a socket for the reception of the relatively wide, flat attaching means 7 provided upon certain forms of lamps, it may be noted that when the 80 openings 13, 14, etc. are cut into a flat blank as above described, the material of said blank is slit upon opposite sides of the portion 21, after which the portion 21, intermediate the 85 said slits is bent or projected outwardly to 90 form the socket-like opening previously referred to.

I claim:

1. A lamp-supporting attachment for miners' caps provided with a plurality of 95 separate and independent means for separately and independently supporting a plurality of kinds of lamps each having a different kind of means for securing the same to the said lamp-supporting attachment. 100

2. As an article of manufacture, a lamp-supporting attachment for miners' caps consisting of a strip of suitable material having a central portion which, when the attachment is secured to a cap, extends in general parallel relation to the body of the same and the upper end of which terminates in a rearwardly extending portion, a portion extending a short distance downwardly from the rear end of the latter portion, and a portion extending rearwardly from the lower end of the said downwardly extending portion, the second mentioned rearwardly extending portion having an opening for the reception of a hook for supporting a miner's lamp and a slot in said strip in front of said opening and in alignment therewith and a plurality of openings in the first named rearwardly extending portion of said strip adapted to receive supporting prongs attached to a lamp, 115 substantially as described. 120

3. As an article of manufacture, a lamp-supporting attachment for miners' caps consisting of a strip of suitable material having a central portion which, when the attachment is secured to a cap, extends in general parallel relation to the body of the same and the upper end of which terminates in a rear- 125

wardly extending portion, a portion extending a short distance downwardly from the rear end of the latter portion, and a portion extending rearwardly from the lower 5 end of the said downwardly extending portion, the second mentioned rearwardly extending portion having an opening for the reception of a hook for supporting a miner's lamp, a slot in said strip in front of said 10 opening and in alinement therewith and a plurality of openings in the first named rearwardly extending portion of said strip, and the said strip also having a relatively narrow portion extending transversely thereof 15 provided by a couple of slits cut in parallel relation to each other, the said portion being pressed outwardly to form a socket for the reception of a relatively wide supporting projection upon a lamp.

20 4. As an article of manufacture, a lamp supporting attachment for miners' caps comprising a strip of suitable material adapted to be secured to the front portion of a cap, the upper portion of said strip intermediate 25 its ends being bent to form a U-shaped portion and the said strip having a portion which extends rearwardly from the rear part of said U-shaped portion and which is adapted to be connected with the top portion of 30 the cap, the said rearwardly extending portion being provided with an opening for the reception of a hook attached to a lamp and the said strip having a slot cut through the 35 said U-shaped portion and extending longitudinally of the said strip and being in alinement with the said opening; and a plurality of openings formed in the connecting part of the said U-shaped portion adapted to re-

ceive supporting prongs attached to a lamp, substantially as described. 40

5. As an article of manufacture, a lamp supporting attachment for miners' caps consisting of a strip of suitable material provided with terminal end portions adapted to be secured to the vizor and to the top of the cap respectively and a central portion arranged in general parallel relation to the side of the cap when the said attachment is secured to the cap, the upper end of said central portion terminating in a rectangular or U-shaped part, the terminal end portion of 45 said strip which is connected to the top of the cap being provided with an opening for the reception of a hook having connection with a lamp, a slot cut through the said U-shaped 50 portion and extending longitudinally of the said strip and being in alinement with the said opening but separated therefrom by a narrow strip of material and the said slot terminating in a relatively wide opening 55 formed in the said central portion, notches formed in the opposite sides of the said slot in the top of said U-shaped portion and additional slots or openings formed in said part in spaced relation to the said notches, the 60 said strip having slits formed in the central portion thereof, the strip of material between the said slits being projected outwardly to form a socket for the reception of a correspondingly shaped shank having connection with a lamp. 65

In testimony that I claim the foregoing as my invention, I have hereunto set my hand this 19th day of June, A. D. 1918.

WILLIAM ISRAEL.
